(57) **CLAIM**

The ornamental design for a multi-leg disc brake rotor, as shown and described.

DESCRIPTION

FIG. 1 is a perspective view of a portion of a disk brake of a rotor showing our new design;

FIG. 2 is a front elevational view thereof;

FIG. 3 is a left side elevational view thereof;

FIG. 4 is a rear elevational view thereof;

FIG. 5 is a perspective view of a disk brake of a rotor showing a second embodiment of our new design;

FIG. 6 is a front elevational view of FIG. 5;

FIG. 7 is a left side elevational view of FIG. 5; and,

FIG. 8 is a rear elevational view of FIG. 5.

The depths, broken lines, and surface shading shown in the figures are for illustrative and environmental purposes only. They do not form a part of the claimed design.
